STOKER

Robert E. Stevenson, Indianapolis, Ind.

Application March 30, 1936, Serial No. 71,585

7 Claims. (Cl. 110—45)

This invention relates to the art of solid fuel stokers and has for one of its primary objects the provision of means for creating combustion of the fuel immediately around the enclosing wall of the combustion chamber rather than having the combustion occur in the central portion of that chamber with a "dead" area therearound as has been the usual practice in the ordinary domestic stoker.

A further primary object of my invention is to provide a very simple and efficient distributing device whereby the fuel as well as the air for supporting combustion is delivered in close proximity to the outer wall of the combustion chamber without the necessity of having to employ moving members immediately adjacent the combustion zone. Another primary object of the invention is to provide means for feeding the fused ashes or clinkers resulting from combustion of the fuel to a central collecting plate from which they may be removed at will or even allowed to collect without interfering with the combustion in the annular zone therearound.

A still further important object of my invention is to provide a structure which may be installed in furnaces previously built without having to build up cement fillers or the like and which will be adaptable through different sizes of filler plates to the varying size of combustion chambers encountered.

These and other objects and advantages of the invention will become apparent to those versed in the art in the following description of my invention as drawn to two possible forms illustrative of the structural embodiment of the invention, as shown in the accompanying drawings, wherein

Fig. 1 is a vertical sectional view through a structure embodying my invention with parts broken away;

Fig. 2, a transverse vertical section on the line 2—2 in Fig. 1;

Fig. 3, a horizontal transverse section with parts broken away on the line 3—3 in Fig. 1, and

Fig. 4, a vertical section of a form of the invention modified from that shown in Fig. 1. Figs. 1 and 4 are in part diagrammatic.

Like characters of reference indicate like parts throughout the several views in the drawings.

The invention may be applied to any of the usual and well known types of heating units, a hot air heating unit being more or less diagrammatically illustrated in the forms herein shown wherein a combustion chamber 10 is shown surrounded by the usual jacket 11 from which hot air is taken for heating purposes. The jacket 11 is provided with a customary ash pit door open-

ing 12 through which I extend the fuel supply conductor 13. This conductor 13 leads within an air box 14 which is provided with an inner cylindrical portion 15 all suitably supported by legs or brackets such as the adjustable bolts 16, as indicated in Figs. 1 and 2.

The fuel supply pipe 13 is carried inwardly in spaced relation through the air box 14 into the cylindrical portion 15 wherein the pipe 13 merges and discharges into an upwardly turned conical end 17 flaring outwardly in its upper portion and forming a seal or closure over the top side of the air box portion 15. Above this end 17 is positioned an inverted conical air chamber 18 mounted in spaced relation in and above the end 17 as indicated in Fig. 1. The air chamber 18 is interconnected with the air box 14 by means of suitable nipples 19 extending across the annular passageway formed between the end 17 and the air chamber 18 thereabove.

The upper side of this chamber 18 is provided with a lid or cover 20 which is preferably mounted thereon to be revoluble in a horizontal plane about a central bolt 21 which has its lower end anchored or secured in the chamber 18. This cover 20 is spaced upwardly from the upper edge of the chamber 18 by means of lugs 22 so as to provide annular slit-openings 22 between the cover and the upper end of the wall of the chamber 18.

The members so far described are mounted in relation to the combustion chamber 10 to have the cover plate 20 at the bottom or in the lower portion of the chamber 10. In order to complete the enclosure of the lower end of the chamber 10 (from which the ordinary grate bars have been removed as is customary) I employ a plurality of filler plates 23 of any suitable number to extend from the top of the juncture of the end 17 with the air box portion 15 in an outwardly flaring manner to meet and rest upon the lower end of the combustion chamber wall or ring 24, this ring being in the ordinary assembly, that which has originally supported the removed grate bars.

These filler plates 23 are made to fit together snugly about their side edges and are made in sets varying in size to meet the requirements of the varying diameters of the combustion chambers encountered. In other words, for each different size of fire pot, there is a specified set of plates 23 to fill in between the wall of that fire pot and the pipe end 17.

In practice, fuel is fed from any suitable hopper 24 in the usual manner by a conveyer screw 25 through the pipe 13 and thereby forced into the discharge end 17 which flares upwardly as above

indicated. Continued feeding of fuel into this end causes the fuel to be forced on up over the plates 23 to assume some such upper positions as indicated by the dotted lines in Fig. 1. Air is forced under pressure from a suitable blower 26 in the usual manner through a conducting pipe 27 into the air box 14 from which it may escape through the nipples 19 into the chamber 18 and discharge therefrom through the openings 22 into the fuel therearound and below the upper level thereof. Combustion of the fuel is had as may be readily understood within this annular zone in immediate proximity to the wall of the chamber 18 where it is practically under the influence of the outwardly flowing air from the openings 22 which tend to create a blast directed toward the walls of the furnace.

It is to be understood that in any hot air type of furnace as herein illustrated, it is the wall of the combustion chamber which is employed to transmit heat from the burning fuel to the air between the jacket and that chamber. Therefore it is appreciated that the heating unit becomes more efficient with the utilization of the heat of combustion to heat these outer walls directly rather than permitting the combustion to occur centrally of the chamber and at a distance removed from the outer wall.

The air chamber 18 is securely anchored by nipples 19 so that the fuel rising therearound does not lift it out of position and the cover 20 is made to be revoluble so that it may be turned from time to time by any means such as a poker being inserted in one of the openings 22 to engage a lug 22' and thereby free the openings of any accumulation of ash or fuel dust that may occur. At times the air pressure in the chamber 18 may not be sufficient to maintain that opening. Such a condition would occur of course during automatic control of the air or fuel or both as is the common practice. It is to be noted that the filler plates 23 have their lower ends anchored around the annular flange of the pipe end 17 so as to prevent outward displacement as the fuel is fed up over the plates. This mounting in the particular form herein shown is accomplished by providing a recess within the lower end of each plate which may fit over a projection such as the head of a bolt 28 employed to interconnect the flange of the pipe end 17 with the air box portion 15, Fig. 1.

In the form herein shown in Fig. 4, the air box of the form shown in Fig. 1 is omitted and an air conductor 29' is carried along under the fuel pipe 13' to discharge directly into the lower end of the chamber 18'. Otherwise the structure remains the same in that fuel is fed by the conveyer screw 25' into the discharging end 17' so that the fuel is carried directly upwardly in an outwardly flaring annular passageway around the chamber 18'. The principal distinction between the form shown in Fig. 4 and that shown in Fig. 1 is in the manner of supplying the air to discharge from the chamber 18' through the openings 22' to support combustion adjacent the outer wall of the combustion chamber.

While I have herein shown and described my invention in the forms as now best known to me, it is obvious that structural variations may be employed without departing from the spirit of the invention and I, therefore, do not desire to be limited to that precise form beyond the limitations which may be imposed by the following claims.

I claim:

1. In an underfeed stoker for supplying solid

fuel to a combustion chamber, means for placing said fuel in the form of an annulus within said chamber and in juxtaposition with the wall thereof, means for directing a blast of air across said fuel annulus toward the chamber wall and a circular rotatable plate covering the center of the annulus and above and aiding in the direction of the air blast, said plate having lugs manually actuated to rotate the plate.

2. In an underfeed stoker, the combination of a fire box having a bottom, a fuel feeding pipe having an upwardly flaring end directly on the discharge end of the pipe spaced below the bottom of the fire box, an inverted conical air distributing chamber spaced in and above the flaring end of the feed pipe, a cover plate closing the upper end of the air distributing chamber, having air outlets between it and the walls of the chamber and lugs by which it is manually rotated, means for supplying air under pressure to the chamber and a closely fitting series of plates closing the space between the flaring end of the fuel feeding pipe and the bottom of the fire box.

3. In an underfeed stoker, in combination with a fire-box provided with an external wall, a fuel feeding pipe below the fire-box extending to the space below the fire box and provided with an upwardly flaring end arranged to discharge into the fire box, an inverted conical air distributing chamber wall located in the upwardly flaring end of the fuel feeding pipe, a cover plate over the upper end of the cone having air outlets next to the walls of the cone directed toward the wall of said fire-box, means for supplying air to the air chamber, and filler plates mounted on said flaring end portion and extending upwardly and outwardly to said wall.

4. In an underfeed stoker, in combination with a fire-box provided with an external wall, a fuel feeding pipe below the fire-box extending to the space below the fire box and provided with an upwardly flaring end arranged to discharge into the fire box, an inverted conical air distributing chamber wall located in the upwardly flaring end of the fuel feeding pipe, a cover plate over the upper end of the cone having air outlets next to the walls of the cone directed toward the wall of said fire-box, means for supplying air to the air chamber, and filler plates mounted on said flaring end portion and extending upwardly and outwardly to said wall, said outlets being at approximately the same elevation as that of the upper ends of said filler plates.

5. In an underfeed stoker, in combination with a fire-box provided with an external wall, a fuel feeding pipe below the fire-box extending to the space below the fire box and provided with an upwardly flaring end arranged to discharge into the fire box, an inverted conical air distributing chamber wall located in the upwardly flaring end of the fuel feeding pipe, a cover plate over the upper end of the cone having air outlets next to the walls of the cone directed toward the wall of said fire-box, means for supplying air to the air chamber, and filler plates mounted on said flaring end portion and extending upwardly and outwardly to said wall, said filler plates being of sufficient number and size to close the space between the fire-box and the top of the flaring end of the fuel pipe.

6. In an underfeed stoker, in combination with a fire-box provided with an external wall, a fuel feeding pipe below the fire-box extending to the space below the fire box and provided with an upwardly flaring end arranged to discharge into

- the fire box, an inverted conical air distributing chamber wall located in the upwardly flaring end of the fuel feeding pipe, a cover plate over the upper end of the cone having air outlets next to the walls of the cone directed toward the wall of said fire box, means for supplying air to the air chamber, and filler plates mounted on said flaring end portion and extending upwardly and outwardly to said wall, and lugs between said plate and conical chamber wall supporting the plate and defining said outlets below the plate.
- 5
7. In an underfeed stoker, the combination with a furnace having an ash pit and ash pit door, and provided with a fire box having a wall, of a fuel supply pipe below the fire box extending through the ash pit door, an air supply con-
- 10 ductor extending with the fuel pipe through said door, an upwardly flaring end connected with the discharge end of said pipe below the fire box, an inverted conical air distributing chamber above said flaring end, a rotatable circular cover limiting the air discharge from the distributing chamber, a plurality of filler plates continuing from the end of said upwardly flaring end of the conductor to the wall of the fire box to define an annular fuel directing passageway and air conducting means interconnecting said air chamber and said air supply conductor, said chamber having air outlets at its upper end directed toward said fire box wall.
